Folding Carton

Abraham Barron, New York, N. Y.

Application April 14, 1933, Serial No. 666,187

10 Claims. (Cl. 229—52)

This invention relates to the class of folding boxes or cartons and, while not restricted to such use, is particularly designed for the purpose of packaging a plurality of bottles whereby they may be safely and conveniently carried by hand or otherwise.

The invention broadly aims to provide a folding box or carton which may be cut and formed from a single sheet of stock, the construction being such that the completed structure may be disposed in an opened flat condition for the storage of a large quantity in a minimum space and which construction further admits of the ready and expeditious setting up of the carton to receive the bottles or other contents without requiring any difficult or complicated operations.

As a further feature the invention comprehends a folding box or carton of the indicated character which serves to completely house and protect the contents and which retains itself in a closed condition irrespective of the position in which the box or carton is carried, held, or set or laid down.

The invention further contemplates a carton or box structure of the character set forth, which is so designed that when it is carried by its handle, the stresses and strains are imparted in such a manner that the various portions thereof brace and counterbrace each other so as to make for an unusually strong and rigid structure.

Other objects of the invention reside in the provision of an improved carton or box which is comparatively simple and not complicated in its construction, which is inexpensive to produce and which is highly efficient for its intended purpose.

With the above recited and other objects in view reference is made to the following specification and the accompanying drawings in which there is described and illustrated a preferred embodiment of the invention which the claims, when taken in connection therewith, mark out and define the actual scope of the invention.

In the drawings:—

Figure 1 is a perspective view of the carton in its set-up closed condition for carrying by its handle.

Figure 2 is a similar view with the handle-forming tabs spread apart and held down in a flattened condition to permit of the storage and shipment of a maximum number of the filled cartons in a minimum space.

Figure 3 is a vertical sectional view on a

larger scale, the same being taken on a plane which is approximately indicated by the line 3—3 in Figure 1.

Figure 4 is a horizontal sectional view taken approximately on the line 4—4 of Figure 3. 60

Figure 5 is a plan view of the carton in its flattened down or folded condition for storage or transportation of the same when unfilled.

Figure 6 is a plan view of the blank from which the carton is formed. 65

Referring to the drawings by characters of reference A and B designate two compartment-forming units which are of identical construction and which are joined together by a link portion or bottom member C, preferably formed integral 70 therewith as shown. Each unit includes an outer wall 10 and an inner wall 11, said walls being joined together by a side wall 12. The opposite longitudinal side edge of the outer wall 10 has a side wall 13 and the lower edge of the outer wall 75 10 is joined to the link portion or bottom member C. The inner wall 11 has at its lower edge a hingedly attached bottom flap 14 which is of slightly lesser length than the width of the inner and outer walls and of slightly lesser width than 80 the width of the side walls 12 and 13 so that the bottom flaps may fit within the bottom of each of the compartment-forming units when the same are set up. The upper edge of each inner wall 11 has a reduced upstanding extension or 85 tab 15, the side edges 16 of which converge upwardly. Each extension or tab 15 is formed with an opening 17 so as to constitute a handle which is double the thickness of the stock when the extensions or tabs are brought together. 90

The upper edge of each outer wall 10 is provided with a top flap 18 having a slot 19 which is of such a size and so positioned as to snugly engage over the lower wider base portion of both of the handle-forming tabs 15, thereby serving 95 the dual function of retaining the top or cover flaps 18 in closed overlapped relation and the units in side-by-side relation.

If desired and as shown partition tongues 20 may be provided for each unit and the same are 100 preferably cut and formed in the inner walls 11. The partition tongues 20 are of such a length that they extend from the inner walls outwardly and bear against the inner face of the outer walls 10 to additionally serve as a transverse brace 105 for the carton structure.

The blank shown in Figure 6 is formed into the completed carton by joining the free side edges 21 of the inner walls 11 with the free side edges 22 of the side walls 13 in any suitable manner to 110

form a hinged joint. As illustrated, the edges 21 and 22 are connected by a strip of material or tape 23. The carton thus produced is shown in a flattened or collapsed condition in Figure 5 so that a large quantity may be thus stored and shipped in a minimum space. If it is desired to reduce the area of the flattened or collapsed cartons, this may be accomplished by providing the link or bottom member C with a transverse score line D so that the units may be folded into overlying relation.

With the article in the collapsed condition as shown in Figure 5, the same may be set up by the following operations: First, the walls 11 of each unit are moved from the offset relation shown to a position where they overlie and are spaced from the walls 10 with the side walls 12 and 13 disposed in parallel relation to each other and in planes perpendicular to the planes of the walls 10 and 11; Second, the bottom flaps 14 are swung inwardly to lie within the confines of the inner or lower ends of the compartments which are thus formed with the free longitudinal edges of the flaps engaging the lower inner edges of the outer walls 10 in the manner shown in Figure 3; Third, with the two compartment-forming units in the opened condition thus described, said units are then swung inwardly toward each other and with reference to the link or bottom member C so that the lower ends of the units overlie said link or bottom member. After the bottles E or other contents have been introduced into the unit compartments, the two handle-forming tabs 15, arranged in side-by-side relation, are flexed laterally and inserted through the slot 19 of one cover flap 18 after which said tabs are flexed laterally in the opposite direction and the slot 19 of the other cover flap is then engaged thereover. The relative size of the tabs and slots are such that a frictional locking engagement is set up which prevents unintentional disengagement, thereby holding the carton structure in a closed condition, which is clearly illustrated in Figures 1 and 3 of the drawings. In this condition the carton may be conveniently carried by inserting the fingers through the registering openings 17 in the handle tabs.

Obviously the bottles may be either disposed in the upright position shown or arranged horizontally by slightly varying the proportions of the carton. It is also evident that in some instances where the product which is to be carried in the carton is packaged at the place of its manufacture, it may be found desirable to spread the handle-forming tabs and secure them down in a flattened condition against the upper end of the carton by suitable means such as an adhesive tape F as shown in Figure 2. In this case only the downturned terminal portions G of the tab are adhesively secured to the outer sides of the carton, so that the tearing or cutting of the tape adjacent the terminals serve to completely release the handle tabs.

With the carton in the setup, filled and closed condition illustrated in Figures 1 and 3, it will be found that in carrying the same by the handle tabs 15, that the weight of the load of the contents is divided and distributed in such a manner that the inner and outer walls as well as the link or bottom member and the bottom flaps brace and counter-brace each other.

What is claimed is:

1. A folding carton including a pair of compartment-defining units each having inner and outer walls, a link member joining the outer

walls and adapted to extend across and completely underlie the lower ends of the units when the carton is in set up condition, a handle-forming tab extending upwardly from the upper edge of the inner wall of each unit, and a cover flap hingedly carried by the upper edge of each outer wall thereof having overlapping registerable slotted portions through which the handle-forming tabs are adapted to extend for holding the inner walls and the handle-forming tabs in flat contact with each other.

2. A folding carton including a pair of compartment-defining units each having inner and outer walls, a link member joining the outer walls and adapted to extend across and completely underlie the lower ends of the units when the carton is in set-up condition, a handle-forming tab extending upwardly from the upper edge of the inner wall of each unit, a cover flap hingedly carried by the upper edge of each outer wall thereof having overlapping registerable slotted portions through which the handle-forming tabs are adapted to extend, and a bottom flap hingedly carried by the lower edge of the inner wall of each unit to respectively fit within the confines of the lower end thereof and to overlie the link member.

3. A folding carton structure fashioned from a sheet of stock and so constructed and arranged as to provide a pair of compartment-defining units, a link member joining the lower outer edges of the units and adapted to underlie the lower ends of both units when the carton is set up, an inwardly directed cover flap at the outer upper edge of each unit having slotted portions adapted to mate and overlap and an upwardly extending handle-forming tab at the inner upper edge of each unit for engagement through said mating overlapped slotted portions of the cover flaps for holding the handle-forming tabs in contact with each other.

4. A folding carton structure fashioned from a sheet of stock and so constructed and arranged as to provide a pair of collapsible compartment-defining units, a link member joining the lower outer edges of the units and adapted to underlie the lower ends of both units when the carton is set up, an inwardly directed cover flap at the outer upper edge of each unit having slotted portions adapted to mate and overlap and an upwardly extending handle-forming tab at the inner upper edge of each unit for engagement through said mating overlapped slotted portions of the cover flaps.

5. A carton including a bottom member and a pair of compartment-forming units each comprising an outer side wall hingedly connected at its lower edge to one of the opposite outer edges of the bottom member, an inner side wall and side edge walls hingedly connecting the inner and outer side walls to permit of collapsing of the units when the carton is in a knocked-down condition, a slotted cover flap hingedly connected to the upper edge of the outer side wall and a handle-forming tab extending upwardly from the upper edge of the inner side wall of each unit and engaging through slotted cover flaps of the units.

6. A carton including a bottom member and a pair of compartment-forming units each comprising an outer side wall hingedly connected at its lower edge to one of the opposite outer edges of the bottom member, an inner side wall and side edge walls hingedly connecting the inner and outer side walls to permit of collapsing of

the units when the carton is in a knocked-down condition, a slotted cover flap hingedly connected to the upper edge of the outer side wall and a handle-forming tab extending upwardly from 5 the upper edge of the inner side wall, and the partition tongues cut from the inner side wall and of a length to extend transversely across the unit to engage with the outer side walls.

7. A carton including independent compartment-forming units for arrangement in side-by-side relation, said units each having inner and outer walls and side walls, a link member connected to the outer side wall of each unit at 10 their bottom edges and underlying the entire bottom of the carton, an extension at the upper end of each of the adjacent inner walls of the units, the said extensions having mating openings so that the extensions together form a handle for the carton.

20 8. A carton including independent compartment-forming units for arrangement in side-by-side relation, said units each having inner and outer walls and side walls, a link member connected to the outer side wall of each unit at 25 their bottom edges and underlying the entire bottom of the carton, an extension at the upper end of each of the adjacent inner walls of the units, the said extensions having mating openings so that the extensions together form a 30 handle for the carton, and means having detachable engagement with said extensions for holding the units in side by side relation and the extensions in mating contact with each other.

35

9. In a carton, a pair of collapsible compartment-forming units, a link member having hinged connections with the outer lower edges of each unit said units when collapsed lying in planes parallel to the plane of the link member and said units being swingable on said hinged connections with the link member and expansible to a set-up position parallel to each other and perpendicular to the plane of the link member with the lower ends of said units closed by said link member, inwardly foldable cover flaps at the outer upper edges of said units having slotted portions adapted to be arranged in overlapped relation with the slots in registry and upwardly projecting handle-forming tabs engageable through the overlapped registered slotted portions. 80

10. In a carton, a pair of collapsible compartment-forming units, a link member having hinged connections with the outer lower edges of each unit said units when collapsed lying in planes parallel to the plane of the link member and said units being swingable on said hinged connections with the link member and expansible to a set-up position parallel to each other 85 and perpendicular to the plane of the link member with the lower ends of said units closed by said link member, inwardly foldable cover flaps at the outer upper edges of said units having slotted portions adapted to be arranged 90 in overlapped relation with the slots in registry.
